CLAIM

The ornamental design for a transparent storage bin, as shown and described.

DESCRIPTION

FIG. 1 is a right side perspective view of a transparent storage bin showing the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

The stippling that can be seen on the bottom portion of the claimed design is a type of shading that represents a type of transparent surface.

The broken lines are for the purpose of illustrating the environment of the article only and form no part of the claimed design.
